CLAIM

The ornamental design for a light bulb as shown and described.

DESCRIPTION

FIG. 1 is a front, perspective view of the embodiment of a light bulb showing our new design;

FIG. 2 is a front view of the embodiment of a light bulb;

FIG. 3 is a rear view of the embodiment of a light bulb;

FIG. 4 is a left side view of the embodiment of a light bulb;

FIG. 5 is a right side view of the embodiment of a light bulb;

FIG. 6 is a top plan view of the embodiment of a light bulb; and,

FIG. 7 is a bottom plan view of the embodiment of a light bulb.

The broken lines in the drawing depict portions of the light bulb form no part of the claimed design.
